UNITED STATES PATENT OFFICE.

HAROLD F. HAGEN, OF JERSEY CITY, NEW JERSEY, ASSIGNOR TO THE GREEN FUEL ECONOMIZER COMPANY, OF MATTEAWAN, NEW YORK, A CORPORATION OF NEW YORK.

CONICAL-FLOW FAN.

1,199,374.

Specification of Letters Patent. Patented Sept. 26, 1916.

Application filed January 13, 1913. Serial No. 741,717.

To all whom it may concern:

Be it known that I, HAROLD F. HAGEN, a citizen of the United States, residing at Jersey City, New Jersey, have invented 5 certain new and useful Improvements in Conical-Flow Fans, of which the following is a full, clear, and exact description.

The invention which constitutes the subject matter of this application, relates to 10 a diffuser applicable to fans, compressors, pumps and other kindred apparatus.

It is well known that the axial flow or propeller type of fan is especially desirable where large quantities of air are to be 15 moved but only against comparatively low pressures. It is also known that with the radial flow fan, generally called the centrifugal fan, it is extremely difficult to secure a large volume of air at a moderate 20 pressure and still secure a high efficiency unless the fans are made of a very large size so that the velocities of the fluid through the passages are such as to make the velocity heads small.

25 Radial flow fans necessitate the turning of the air through a right angle, and inasmuch as a large volume at moderate pressure requires large air passages, it is difficult to secure, mainly on account of the above 30 mentioned right angle turn, an even distribution of the air. As a result radial fans designed for large volumes, work rather inefficiently.

Any rotating impeller which imparts 35 energy to a fluid passing through it, must give the particles of that fluid a rotative velocity component in the direction of the rotation of the impeller. This rotative velocity component is in fact a measure of 40 the amount of work done by the fan. Consequently if the volume delivered is constant a fan developing a high pressure, that is doing a large amount of work, will necessarily impart to the fluid particles a rather 45 large rotative velocity component; and a fan working at a low pressure, doing a small amount of work will impart to the fluid particles a smaller rotative velocity component. In a radial fan, this component of the velocity is useful and appears, 50 though somewhat diffused, as useful velocity head at the outside of the volute. But in the axial flow fan the head represented by the rotative velocity component at the

fan outlet is entirely lost. It serves no useful purpose in moving the fluid through the passages. For this reason an axial flow fan cannot work efficiently at other than very low pressure where this waste energy is small.

55 I have found in all fans as hitherto constructed that the sides of the walls have not had the proper relation with respect to each other and the direction of the flow of the fluid therethrough inasmuch as the 60 stream does not fill the space between the walls owing to the fact that the area of the space always increases in the direction of flow whereas the area should remain substantially constant in order to obtain the 65 best results in the conversion of the rotative velocity energy into pressure energy.

The invention therefore consists in providing mechanism for converting this rotative velocity of the axial or propeller type 70 fans, with their excellent distribution of the fluid, into higher pressures with good efficiencies, by providing a diffuser therefor of the type described in detail below. This 75 diffuser is employed to provide an efficient 80 means for converting the rotative kinetic energy into useful potential energy or static pressure through the action of the law of the constancy of the moment of momentum. This diffuser therefore may be 85 applied to an axial fan thereby increasing its pressure range and its efficiency.

Referring to the drawings, wherein I 90 show the preferred embodiments of my invention; Figure 1 shows a construction of a fan embodying the principle of my invention wherein the inner and outer co-axial walls of the diffuser are curved concavely with respect to the axis of the fan. Fig. 2 95 illustrates a modified construction which is an approximation of the device shown in Fig. 1. Fig. 3 shows a construction of a fan embodying the principle of my invention, the walls of which are curved in a direction which is convex to the axis of the 100 fan and approach each other as the radial distance increases. Fig. 4 illustrates a modification which is an approximation of the device shown in Fig. 3.

The essential feature of my invention, as 105 will appear from the embodiment shown, consists in the provision of a space which is substantially free from eddies and is ac-

complished by employing co-axial members the walls of which are so inclined to the axis that they approach each other as the radial distance from the axis increases.

5 Referring specifically to Fig. 1, the character A represents the interior wall or member and the character B the exterior member which is co-axial with the member A both of which are stationarily mounted, 10 the member B preferably secured to the suction ring C by means of bolts shown at D, and the member A is preferably secured to the member B by the means shown at E. The suction ring is in turn preferably supported 15 by a suitable base, such as shown at F. The surface of the members or walls A and B are connected by strap-iron supports and approach each other in the direction of flow of the gases therethrough in the manner 20 above stated. As a result of so placing the two surfaces not only is the forward velocity of the entering fluid diffused, but the circumferential velocity is diffused as well.

Fig. 2 shows a construction similar to the 25 construction shown in Fig. 1; but in this case the members A and B are co-axial conical members and are so arranged, as in Fig. 1, that the area between the surfaces, that is the area these surfaces intercept on planes 30 perpendicular to the axis of the shaft, is substantially constant, and the walls of the diffuser are inclined toward each other in the direction of the flow of fluid therethrough. For instance, this area at the 35 point of entrance of the fluid between said surfaces is equal or substantially equal to this same area at the point of exit of said fluid.

In Fig. 3 I have shown the same principles embodied in a diffuser wherein the 40 walls A and B are curved reversely to the curvature of the walls shown in Fig. 1, and also approach each other as the radial distance from the axis of the fan increases. The 45 device is so constructed that the sectional area at increasing radial distances is substantially constant, or very slightly decreasing, and the formation of the path of the fluid through the fan is changed from an axial 50 into a substantially conical direction.

Fig. 4 shows a form of diffuser which approximates the walls of the construction shown in Fig. 3 and for practical purposes, like the construction shown in Fig. 2, may 55 be used with substantially the same efficiency. These defining walls like those shown in Fig. 2, are also co-axial conical members the outer surfaces of which are inclined toward each other in the direction of the 60 flow of fluid therethrough.

With reference to the construction of my 65 conical flow diffusers as shown in Figs. 1 and 3, the exact inclination of the walls is perfectly determined in accordance with the theory of whirl-free stream line motion. In

my investigations, however, I have found that the limiting walls of the diffuser to be in exact accordance with this theory will be curved, either concavely or convexly with respect to the axis of the flow, and approach 70 each other as the radial distance from the axis of the fan increases. I have also found that these walls can be curved differently with respect to the axis of the fan and of course each will be expressed by different 75 mathematical equations or formulae. I give one of the mathematical equations of my invention below:

$$\text{Equation 1: } K = Cx - Dr^2$$

80

where C is a constant, x the axial distance from the origin and D is another constant. This equation is the formula of a parabola and is arrived at from the underlying principles of the theory of whirl-free stream line 85 motion. In order to avoid the prolixity of description I will not enter into a discussion of the necessary steps in arriving at the conclusion, as it is thought that this will be clearly understood by those skilled in this 90 particular art. By regarding K as the parameter and assigning to it different values the equation may be considered to represent a family of congruent parabolas. Using these to represent a fluid flow, we 95 have a mathematical expression of the action of the fluid. Any two of the congruent parabolas may be taken as the limiting walls of the diffuser and through this passage, defined by the limiting walls, the fluid can flow 100 free from whirling motion. A construction in accordance with this equation is illustrated in Fig. 1, in which the curves are concave toward the axis of the fan. From the underlying principles of the whirl-free 105 theory other formulae may be developed and the limiting walls of the diffuser constructed in accordance therewith to provide a substantially conical passage through which the fluid can flow free from whirling motion. 110

Another mathematical equation which may be evolved from the underlying principle of whirl-free stream line motion is the following:

$$\text{Equation 2: } K = C \left(\frac{r^2}{2} \log. r - \frac{x^2}{2} \right)$$

115

where C is a constant, r the radial distance from the axis of the fan, and x the axial distance from an origin. By regarding K 120 as the parameter and assigning to it different values the equation will be found to represent another family of curves which approach each other as the radial distance from the axis of the fan increases. In using 125 these curves again to represent a fluid flow we have a mathematical expression of the action of the fluid any two of which may be taken as the limiting walls of the diffuser which walls define a passage free from 130

- whirling motion. A diffuser constructed in accordance with this equation is illustrated in Fig. 3 in which the curves are shown as being convex toward the axis of the fan.
- 5 As in the case of the diffuser illustrated in Fig. 1 other formulæ may be developed and the limiting walls of the diffuser constructed in accordance therewith to provide a passage through which the fluid can flow free
- 10 from whirling motion. Of course in designing a diffuser the values assigned to the constants of these equations must be selected with due regard to the nature of the fluids. It will be apparent, however, that in
- 15 the construction shown in Fig. 3 the change of width of the passage formed by the limiting walls of the diffuser is greater owing to the fact that the radial component of the velocity increases more rapidly with respect
- 20 to the axial component than is the case with constructions made from formulæ which represent lines curved reversely from the lines illustrated in said Fig. 3.

I have also found as a matter of fact that

25 if conical walls, such as shown in Figs. 2 and 4, and having substantially the same degree of inclination, be substituted for the curved walls they give a result in operation which approximates the efficiency derived from the

30 curved walls and are preferred in actual practice where diffusers manufactured from sheet metal are required and in these cases the flow of fluid through the passage will be substantially whirl free.

35 It will be very apparent from the above description that large changes in the velocity of the fluid will be effectively avoided in passing through the diffuser. As a result, the formation of eddies is prevented

40 and the flow through the passage whirl-free.

In all the embodiments herein shown an

impeller with suitable blades G is used, properly disposed upon the shaft H.

It is to be understood that I do not limit myself to the exact constructions shown, as many changes may be made in points of detail and other embodiments resorted to without necessarily departing from the spirit and scope of the invention as defined by the appended claims.

What I claim is:

1. In combination, a rotary impeller and a diffuser comprising inner and outer walls or casings defining a substantially conical passage for the flow of fluid therethrough, said walls so related that the areas they intercept on the surface of cylinders coaxial with the axis of the impeller increases substantially in direct proportion to the radius 55 of such cylinders and also the area intercepted by said diffuser walls on planes perpendicular to the axis of the impeller is substantially a constant, whereby the radial and rotational velocity components are decreased 60 while the axial velocity component is kept constant, and a conversion from velocity to pressure is secured and eddies are avoided.

2. In combination, a rotary impeller, and a diffuser comprising outer and inner limiting walls or casings defining a substantially conical passage for the flow of fluid therethrough, said walls so inclined to the axis that they approach each other as the radius increases, and continue throughout their 70 75 whole extent the same direction of curvature toward the axis as the limiting walls of the impeller with which they are combined.

In testimony whereof I affix my signature in the presence of two subscribing witnesses. 80

- whirling motion. A diffuser constructed in accordance with this equation is illustrated in Fig. 3 in which the curves are shown as being convex toward the axis of the fan.
- 5 As in the case of the diffuser illustrated in Fig. 1 other formulae may be developed and the limiting walls of the diffuser constructed in accordance therewith to provide a passage through which the fluid can flow free
- 10 from whirling motion. Of course in designing a diffuser the values assigned to the constants of these equations must be selected with due regard to the nature of the fluids. It will be apparent, however, that in
- 15 the construction shown in Fig. 3 the change of width of the passage formed by the limiting walls of the diffuser is greater owing to the fact that the radial component of the velocity increases more rapidly with respect
- 20 to the axial component than is the case with constructions made from formulae which represent lines curved reversely from the lines illustrated in said Fig. 3.
- I have also found as a matter of fact that
- 25 if conical walls, such as shown in Figs. 2 and 4, and having substantially the same degree of inclination, be substituted for the curved walls they give a result in operation which approximates the efficiency derived from the
- 30 curved walls and are preferred in actual practice where diffusers manufactured from sheet metal are required and in these cases the flow of fluid through the passage will be substantially whirl free.
- 35 It will be very apparent from the above description that large changes in the velocity of the fluid will be effectively avoided in passing through the diffuser. As a result, the formation of eddies is prevented
- 40 and the flow through the passage whirl-free.

In all the embodiments herein shown an

impeller with suitable blades G is used, properly disposed upon the shaft H.

It is to be understood that I do not limit myself to the exact constructions shown, as many changes may be made in points of detail and other embodiments resorted to without necessarily departing from the spirit and scope of the invention as defined by the appended claims.

What I claim is:

1. In combination, a rotary impeller and a diffuser comprising inner and outer walls or casings defining a substantially conical passage for the flow of fluid therethrough, said walls so related that the areas they intercept on the surface of cylinders coaxial with the axis of the impeller increases substantially in direct proportion to the radius of such cylinders and also the area intercepted by said diffuser walls on planes perpendicular to the axis of the impeller is substantially a constant, whereby the radial and rotational velocity components are decreased while the axial velocity component is kept constant, and a conversion from velocity to pressure is secured and eddies are avoided.

2. In combination, a rotary impeller, and a diffuser comprising outer and inner limiting walls or casings defining a substantially conical passage for the flow of fluid therethrough, said walls so inclined to the axis that they approach each other as the radius increases, and continue throughout their whole extent the same direction of curvature toward the axis as the limiting walls of the impeller with which they are combined.

In testimony whereof I affix my signature in the presence of two subscribing witnesses.
